UNITED STATES PATENT OFFICE.

CHRISTIAN J. WEINMAN AND EDWARD E. EUCHENHOFER, OF DAYTON, OHIO.

DESIGN FOR A GAS-ENGINE FRAME.

SPECIFICATION forming part of Design No. 24,728, dated October 1, 1895.

Application filed April 8, 1895. Serial No. 545,000. Term of patent 14 years.

To all whom it may concern:

Be it known that we, CHRISTIAN J. WEINMAN and EDWARD E. EUCHENHOFER, citizens of the United States, residing at Dayton, in the county of Montgomery and State of Ohio, have invented and produced a new and original Design for a Gas-Engine Cylinder and Frame, of which the following is a specification, reference being had therein to the accompanying drawings.

This invention relates to a new and original design for a gas-engine cylinder and frame.

The leading feature of our design consists of a frame having flat sides, projecting wings, and a substantially flat bottom, a top curved near one end, and a transverse opening substantially the same shape as the outline but indented by the upper part of the wings.

In the accompanying drawings, Figure 1 is a perspective view of a gas-engine frame and cylinder embodying our design, and Fig. 2 a cross-section of the frame.

Our new design of frame consists in a substantially flat bottom or base A, substantially rectangular, and an upper body B nearly upright at the ends with a curved corner C and a top generally inclining from such curved corner to the other end. This latter portion of the body is also rounded on the upper exterior. A raised ledge D is formed at the sides with the lower part E of the bearing. A semicircular cap F fits upon the ledge D and has formed on it the remaining part G of the

bearing. A flat surface or plate H surmounts the curved upper part. A removable door I 35 is fitted to one end and forms a raised surface or panel in appearance. This frame is further fashioned with a lateral opening whose upper wall J and end wall K and lower wall L are respectively nearly parallel with the exterior outline opposite to them, while a curved wall M unites the walls J and L. Between the walls K and L is formed another wall consisting of straight parts O and P and an intermediate curved part Q, which three walls 45 form the lower half of a bearing; and these walls are surmounted by a cap R of similar outline. Ribs S run off from the wall Q.

Our design further consists of a cylindrical body T, constituting a cylinder joined onto 50 one end of the frame and surmounted by a boss U and a rectangular chest V, the cylinder having the appearance of projecting from and being sustained by one end of the frame.

Having thus fully described our invention, 55 what we claim as new, and desire to secure by Letters Patent, is—

The design for a gas engine frame herein shown and described.

In testimony whereof we affix our signatures in presence of two witnesses.

CHRISTIAN J. WEINMAN.

EDWARD E. EUCHENHOFER.
